UNITED STATES PATENT OFFICE.

GILBERT R. UPHAM, OF PHILADELPHIA, PENNSYLVANIA, ASSIGNOR TO THE DE LONG HOOK AND EYE COMPANY, OF PHILADELPHIA, PENNSYLVANIA, A CORPORATION OF PENNSYLVANIA.

LAUNDRY-MARKING PIN.

Application filed July 13, 1922. Serial No. 574,598.

To all whom it may concern:

Be it known that I, GILBERT R. UPHAM, a citizen of the United States, and a resident of Philadelphia, in the county of Philadelphia and State of Pennsylvania, have invented an Improvement in Laundry-Marking Pins, of which the following is a specification.

My invention relates to laundry marking pins of safety pin character in which the pointed free end portion of the pin is adapted to be held in place by a shield and it has for its object to provide novel means whereby the free end portion is prevented from becoming accidentally disengaged from said shield.

A further object of the invention is to provide a spring element in such relation to the outer end portion of the shield that it is adapted to prevent accidental disengagement of the free end portion of the pin from the said shield, but does not interfere with the operation of engaging the portion with the said shield.

The invention comprehends the novel construction of means as hereinafter fully described in the specification and particularly pointed out and defined in the claims.

In order that the invention may be readily understood and its practical advantages more fully appreciated reference may be had to the accompanying drawing in which one form of mechanical embodiment thereof is shown. However, it will be understood that changes in the details of construction may be made within the scope of the claims without departing from the invention.

In the drawing:

Fig. 1 is a perspective view of a laundry marking pin embodying my invention; and

Fig. 2 is a transverse sectional view taken on the line 2—2 of Fig. 1.

Referring to the drawing: 1 designates what may be termed the base portion of the pin and 2 the pointed portion thereof. These two portions are connected by a turn in the wire as indicated at 3. The presence of such turn increases the tendency of the pointed free end portion 2 of the pin to press against the inner side of the shield 4, and also causes the portion 2 to open or move away from the base portion 1 when released from the said shield. The shield

consists of a hooked portion as shown in Figs. 1 and 2 which is integral with the plate 5 upon which the identification marks are placed. The end of the base portion 1 of the pin is secured to the marking plate 5 by means of a tongue-like portion 6 which is bent over as indicated in Fig. 1 to clamp and hold the end portion of the base part 1. The plate 5 is provided near its inner end with a couple of parallel slits which extend transversely thereof to form a strip 7 which is pressed inwardly toward the extended depending portion 8 of the shield 4 to form a resilient spring acting abutment, the distance of which from the inner side of the portion 8 of the shield is less than the diameter of the portion 2 of the pin structure. However, because of the resiliency and yielding character of the abutment 7 the end portion of the part 2 of the pin structure may be inserted into and removed from the space within the shield 4 without difficulty. The portion 8 of the shield is substantially parallel with the plates.

Pins of the character shown are attached to articles which are being laundered or they may be attached to net bags which contain such articles. The identification mark, such as a number, which appears upon the plate 5 enables the person in charge to identify the article after it has been laundered. It will be seen that it is of importance that means be provided for preventing as far as may be possible the disengagement of the pointed end portion 2 of the pin from the shield 4 which would be apt to be followed by a separation of the pin from the article intended to be identified.

Having thus described my invention what I claim and desire to secure by Letters Patent is:

1. A laundry marking pin comprising a plate having a hook-projection thereon, a bent wire portion consisting of a base part and a penetrating part which is adapted to engage said hook-projection, and the said plate having transversely extending slits therein, which slits are spaced from each other, and a strip formed by said slits, which strip is integral at its opposite ends with said plate and is bent inwardly toward the outer free end portion of said hook-projection, substantially as described.

2. A laundry marking pin comprising a

plate upon which identifying means is adapted to be placed, the said plate having a hook-projection upon its inner end portion, the outer free end portion of the said hook-projection being spaced from the said plate, the said plate being provided with a couple of slits extending transversely thereof and terminating adjacent the opposite edges thereof and a narrow strip portion situated intermediate the said slits which strip is integral at its opposite ends with said plate and is bowed outwardly toward the outer free end portion of the said hook-projection, and a wire portion having a base part secured to the said plate adjacent its edge opposite the said hook-projection and also having a penetrating part which is adapted to be passed between the said strip and the said outer free end portion of the said hook-projection into and out of engagement with the latter.

3. A laundry marking pin comprising a plate having a hook-projection the outer free end of which is situated in spaced relation to said plate and a yielding resilient strip bent inwardly toward said hook-projection, the opposite ends of which are integral with the said plate and the opposite edges of which are free from and are movable with respect to said plate, and a wire pin portion having a base part secured to said plate adjacent the edge thereof opposite said hook-projection and a penetrating part, the outer free end portion of which is adapted to pass between the said strip and the outer free end portion of said hook-projection into and out of engagement with the latter.

In testimony that I claim the foregoing as my invention I have hereunto signed my name this 11th day of July, A. D., 1922.

GILBERT R. UPHAM.
